James R. Hyde, of Troy, N.Y.
Letters Patent No. 1659, dated Sept. 23, 1862,

The schedule referred to in these Letters Patent and making part of the same,
To all whom it may concern:

Be it known that I, James R. Hyde, of the City of Troy, in the County of Rensselaer, and State of New York, have invented or produced a new and original ornamental design for Cooking Stoves, of which the following is a full and exact description, reference being had to the annexed photographic drawings in which.

Fig. 1. is a front view, and
Fig. 2. a side view of a Cooking stove having my
said design.

Arrange on the panels of the oven doors, A. A. Fig. 2. made with the outer upper corners b. b. rounded, the plaid checked work c. c. surrounded by the vine like ornamental moulding, d. and form on the side plate E, the plaid check drapery f. along the upper part, the swelling and contracting plaid check ground g. along the bottom part, and the plaid work h. inclosed by the arched moulding i. along the forward portion; and dispose on the rectangular panels of the ash box doors J. J. Fig. 1. the diamonded checked ground work k. k. surrounded by the vine like ornamental moulding l. l. on the plain surface, m. m. with the ornaments n. and ornament the front plate, S. with the two way plaid checked ground work p. p. the shield q. and the vine like ornaments r. r. and decorate the upper doors S. S. with the panel forming vine like mouldings t. t. surrounded by the rib work ground u. all as shown by the annexed photographs.

What I claim as new and of my invention or production and desire to secure by Letters Patent is, a cooking stove having plates ornamented as above described.
